CIRCUIT INTERRUPTING APPARATUS

Maurice E. Reagan, Forest Hills, Pa., assignor to
 Westinghouse Electric & Manufacturing Company, East Pittsburgh, Pa., a corporation of Pennsylvania

Application September 3, 1938, Serial No. 228,331

21 Claims. (Cl. 175—294)

The invention relates to circuit interrupters in general and more particularly to operating means for circuit breakers.

Circuit breakers are usually provided with operating means including closing means, latching means or toggle devices for maintaining the breaker closed, and circuits for causing opening or closing of the breaker.

In cases of certain types of mechanical and/or electrical failures of parts of the circuit breaker operating means as, for example, if the latch means for holding the breaker closed becomes defective or if the tripping means sticks in tripping position, the operating means will cause the breaker to continue opening and immediately closing in rapid succession as long as the closing control switch is held closed. This action is known as pumping of the breaker. This pumping action will also result in the event that the operator holds or leaves the closing control switch in closed position and there is a continuing fault on the line. Under these conditions also the breaker will open and immediately close as long as the fault condition is present and the control switch is maintained in closed position. It is desirable, therefore, to provide some means to limit the number of these continuous opening and immediate closing operations or pumping action of the breaker.

An object of the invention is the provision of a circuit breaker operating means with a means which is operable only after the circuit breaker has opened and immediately attempted to close a predetermined number of times in rapid succession, to prevent further closing of the breaker.

Another object of the invention is the provision of a circuit breaker operating means with a means for limiting the number of opening and immediate closing operations which occur in rapid succession when certain parts of the operating means are defective and the closing control switch is held closed, or when an operator holds or leaves the closing control switch closed against a continuing fault in the line or apparatus controlled by the breaker.

Another object of the invention is the provision of a circuit breaker operating means embodying a device in which energy is stored at each operation of the breaker and slowly dissipated thereafter, the device being operable only after a predetermined number of opening and immediate closing operations have occurred in rapid succession.

To prevent the circuit breaker from being opened and immediately closed continuously, i. e. 55

from pumping as a result of the abnormal conditions previously described, there is provided, in accordance with the invention, an energy storing device in which an increment of energy is stored on each operation of the breaker. If the energy thus applied to the storing device attains a predetermined magnitude, the storing device discharges the accumulated energy through a device which causes the circuit breaker to remain permanently open. On the other hand, if the circuit breaker should remain permanently closed or open before the energy stored attains the predetermined value, the energy is dissipated, the energy being dissipated at a predetermined slow rate after each operation of the breaker.

In accordance with the invention, the energy may be stored in the form of electrical energy in capacitors, reactors or the like, in the form 20 of mechanical energy as in a spring or in the form of pneumatic or hydraulic energy as in a fluid pressure device.

The novel features that are considered characteristic of my invention are set forth with particularity in the appended claims. The invention itself, however, both as to its organization and its method of operation, together with additional objects and advantages thereof will best be understood from the following description of 30 specific embodiments when read in connection with the accompanying drawings, in which:

Fig. 1 is a diagrammatic view showing an embodiment of the invention in which the storage of electrical energy is used to prevent continuous opening and immediate closing operations or pumping of a circuit breaker,

Fig. 2 is a diagrammatic view showing a modification of the invention,

Fig. 3 is a diagrammatic view showing an embodiment of the invention in which the storage of pneumatic or hydraulic energy is used to prevent continuous opening and immediate closing operations or pumping of a circuit breaker, and

Fig. 4 is a diagrammatic view showing an embodiment of the invention in which the storage of mechanical energy is used to prevent continuous opening and immediate closing operations or pumping of a circuit breaker.

In Fig. 1, apparatus is shown in which a circuit breaker mechanism 71 of conventional type is prevented from continuously opening and immediately closing, i. e., from pumping as a result of failure of some part or parts of the operating means, such for example as a defective latch, or if the operator holds the closing control switch

closed against a continuing fault condition on the line. The closing coil 73 of the circuit interrupter 71 is energized through the contactor 75 of a closing relay 77 from direct current supply conductors 13 and 15. The closing operation is initiated by a control switch 79 which closes a circuit through the exciting coil 81 of the closing relay 77. The closing relay 77 is actuated and closes its contactor 75 to effect energization of the closing coil 73. The relay is also locked in its actuated position in a circuit which extends from the positive line conductor 13 through a conductor 83, a lock-in contactor 85 of the relay 77, the exciting coil 81 of the relay, a normally closed movable contactor 87 of another auxiliary relay 89, the lowest auxiliary switch 91 of the circuit interrupter, which is closed when the breaker is open and which is open an instant before the breaker reaches the fully closed position, a conductor 95 to the negative line conductor 15.

Since the closing coil 73 is energized through the contactor 75, the circuit breaker closes and is locked in the closed position by the latch 97. The lowest auxiliary switch 91 of the circuit breaker is opened when the breaker reaches closed position and, therefore, the closing relay 77 is deenergized. The circuit through the closing coil 73 is, therefore, opened and the coil is deenergized. If the latch 97 is in proper operating condition, the circuit breaker 71 remains in closed position.

The control switch 79, instead of being of the push button type which is shown spring biased to open position, may be of the knife type, in which instance the closing relay 77 need not be provided with a locking circuit.

If the latch 97 of the circuit breaker should, however, happen to be defective, the breaker will open immediately. Under these conditions, if the control switch 79 is still held in closed position, the closing relay 77 will be again energized and the above operation repeated. The opening and immediate closing operations of the circuit breaker may thus continue indefinitely as long as the control switch is held closed, with damage not only to the circuit breaker but also to the loads supplied from the main line closed by the breaker.

In accordance with the invention, these continued successive openings and immediate closing operations or pumping actions of the circuit breaker are prevented, by causing the auxiliary relay 89 to automatically open its normally closed contactor 87 only after a predetermined number of opening and immediate closing operations have occurred in continuous succession.

The auxiliary relay 89 is of the type that requires a predetermined potential difference for its operation. The potential difference necessary is supplied by charging a reservoir capacitor 99 in circuit with the coil 101 of the relay in increments until the desired potential difference is attained. The increments are measured out by first charging a supply capacitor 103 from the direct current supply conductors 13 and 15 and then discharging the latter capacitor into the reservoir capacitor 99.

The supply capacitor 103 is connected in a circuit which extends from the positive supply conductor 13 through a conductor 105, the upper auxiliary switch 107 of the circuit breaker, which is closed when the circuit interrupter is open, a resistor 109, the capacitor 103 to the negative supply conductor 15. On each opening opera-

tion of the circuit interrupter 71, the supply capacitor 103 is charged to a potential limited by the resistor 109 by current flow through this circuit. When the closing coil 73 closes the circuit interrupter 71, the upper auxiliary switch 107 of the circuit interrupter is opened and a central auxiliary switch 111 thereon is closed. The latter auxiliary switch 111 connects the supply capacitor 103 in series with the reservoir capacitor 99. Thus on each closing operation the charge stored in the supply capacitor 103 is, therefore, transferred to the reservoir capacitor 99.

The reservoir capacitor 99 is connected in series with another resistor 113 and the exciting coil 101 of the auxiliary relay 89. As the circuit interrupter 71 is opened and closed in rapid succession by reason of a defective part, a charge accumulates on the capacitor 99 and after a predetermined number of such successive operations, the potential difference between the plates of the capacitor become sufficient to operate the auxiliary relay 89. The lower movable contactor 87 of the relay is now opened, and, the circuit through the exciting coil 81 of the closing relay 77 is opened. The auxiliary relay 89 is maintained permanently in actuated position through its upper lock in contactor 115 which connects the exciting coil 101 across the supply conductors 13-15 through the resistor 113. The circuit breaker is now maintained in a permanently open condition until it is repaired.

The invention thus prevents the continuous opening and immediate closing operations or pumping action resulting from a defective part, when the control switch 79 is held closed, or if an operator holds or leaves the closing control switch closed against a continuing fault condition on the line.

During normal opening and closing operations of the breaker and even after a number of quick successive operations have occurred but less than the quick successive number required to cause operation of the relay 89, the charge on the capacitor 99 in circuit with the exciting coil 101 of the second auxiliary relay 89 is slowly dissipated through the exciting coil 101 and the resistor 113 in series therewith. Thus the lock out feature is only effective when a predetermined number of opening and immediate closing operations occur in quick succession.

The modification shown in Fig. 2 is largely similar to the embodiment shown in Fig. 1. However, in this case the anti-pumping feature takes place through an electric discharge valve 117. The latter may be of the high vacuum or arc-like type but is preferably the latter. It comprises an anode 119, a cathode 121 and a control electrode 123. Anode-cathode potential is supplied to the relay from the supply conductors 13-15 and the discharge current when it flows energizes the exciting coil 101 of the auxiliary relay 89. The anode-cathode circuit for the discharge valve 117 extends from the positive supply conductor 13 through the conductor 83, the exciting coil 101 of the auxiliary relay 89, the anode 119 and the cathode 121 of the valve, a conductor 125 to the negative line conductor 15.

Normally, the discharge valve is maintained in non-conductive condition by a biasing potential 127 connected between the control electrode 123 and the cathode 121 through a grid resistor 129. The bias potential 127 is counteracted by the operation of a glow discharge tube 131 and a re-

sistor 133 which are in series connection between the control electrode 123 and the cathode 121 and are, therefore, in series with the biasing source 127 and the grid resistor 129. The glow tube 131 has the usual property of becoming conductive when a potential of sufficient magnitude is impressed between its electrodes 135 and 137. The reservoir capacitor 99 is connected in parallel with the resistor 133. The connection is such that the lower plate 139 which becomes electrically positive during the charging operations is connected to the connection point of the glow tube electrode 137 and the resistor 133. When the potential difference on the capacitor 99 becomes sufficiently large, the glow tube 131 becomes conductive and current flows through the glow tube 131 and the grid resistor 129. The current flow from the capacitor 99 through the glow tube 131 takes place in a direction from the lower plate 139 through the tube 131, the resistor 129 to the upper plate 141. The potential drop arising from the current flow through the grid resistor 129 is, therefore, in a direction such that the terminal of the resistor connected to the control electrode 123 of the valve 117 is more positive than the terminal connected to the biasing source 127 and, therefore, the polarity of the potential drop is such that it counteracts the biasing potential 127 and renders the valve conductive. When this occurs, the auxiliary relay 89 is actuated and locked in the actuated position through its upper contactor 115. The circuit through the closing relay 77 is opened through the lower contactor 87 of the relay 89, and continued pumping operation of the circuit breaker is prevented even though the control switch is held in closed position.

It is to be noted again that if the circuit breaker operates properly, the reservoir capacitor 99 is, in this case, discharged through the resistor 133.

In the Fig. 3 modification, a piston 143 which slides in a small air cylinder 145 of an air pump in communication with an air reservoir 147 is moved with the core 149 of the circuit interrupter closing means 73. When the closing coil 73 is energized to close the circuit interrupter 71, the air in the cylinder 145 is compressed and transferred to the air reservoir 147 increasing the pressure in the reservoir. The pressure in the reservoir 147 is communicated through a tube 153 to a diaphragm 155 which when the pressure becomes sufficiently large, is actuated, thereby moving a bar 157 downwardly and causing a contactor 159 attached to the bar to open against the action of a spring 161. The bar 157 is adapted to be latched in the down position by a latch 163. The contactor 159 is connected in circuit with the closing relay coil 81 which initiates the closing operation in the same manner as the closing contactors 75 of the closing relays 77 in the embodiments shown in Fig. 1 and Fig. 2. When the contactor 159 is open, further closing of the circuit breaker is prevented. If a proper closing operation of the circuit breaker takes place, the excess air in the reservoir 145 is slowly discharged through a leak valve 165.

In the Figure 4 modification the closing means 167 for the circuit interrupter 71 is provided with a bar 169 which is moved upwardly when the circuit breaker is closed. The bar 169 carries a pawl 171 which, when the bar moves upwardly, rotates a ratchet wheel 173 one notch during each upward motion. The ratchet wheel 173 is rigidly secured to a worm shaft 175 which is rotatable in bearing means (not shown). The bearing means prevents axial displacement of the worm shaft 75

175. The worm shaft is in engagement with an internally worm threaded tube 177 which is rotatable relative to the worm shaft 175 and which is also movable axially on the worm shaft. The tube 177 has a clutch disc 179 of a friction clutch 181 rigidly secured to one end thereof, and also has a weight or inertia member 182 secured to its side. This disc 179 is normally spaced a very small distance from a cooperating clutch disc 183 which is rigidly secured to a shaft 185 mounted in bearings (not shown) in alignment with the worm shaft 175. When the worm shaft is rotated counterclockwise by the rotation of the ratchet wheel one notch, the tube 177 and its clutch disc 179 are advanced on the worm shaft until the clutch disc 179 engages the cooperating clutch disc 183. This takes place almost immediately upon the turning of the worm as the normal space between the discs is very small. As soon as the discs 179 and 183 are engaged the continued counterclockwise turning of the worm shaft 179 causes the tube 177 and its clutch disc 179 to turn with the worm shaft. The clutch disc is maintained in pressure engagement with the clutch disc 183 by the turning of the worm shaft 175 so that the disc 183 and its shaft 185 are also turned in a counterclockwise direction with the worm shaft 175.

The end of the shaft 185 carries an arm 191, and the shaft is secured to one end of a clock spring 187, the other end of the spring being fixed. Rotation of the shaft 185 causes the spring to become flexed.

After each rotation of the ratchet wheel by one notch the spring 187 tends to return the shaft 185 to its initial position, and also imparts motion to the tube 177 through the clutch discs 179 and 183 to cause return of the tube 177 to its original position, in which the clutch discs 40 are disengaged. However, the return movement of the shaft 185 to its original position is retarded and delayed by a governor 189 mounted on the shaft 185 which causes a drag to be applied to the shaft by actuating a friction brake 190. By reason of the retarding action of the governor 189 the successive operations of the pawl 171 when the breaker opens and immediately closes a predetermined number of times in rapid succession causes the shaft 185 to be rotated through a predetermined angle.

The shaft 185 carries at its end the lever 191 which engages a movable contactor 193 when the shaft 185 has moved through a predetermined angle. The engagement of the lever and the element causes the latter to open. The contactor 193 opens a circuit through the exciting coil 81 of the closing relay 71, in the same manner as the contactors 87 and 159 in the other embodiments. A latch 195 is provided for latching the contactor 193 in the open position so that the closing relay is permanently deenergized and the circuit breaker is prevented from further operating.

While the invention has been shown as applied to a circuit breaker operating means in which the breaker when opened remains open until the manually operable closing control switch is closed, the invention may also be embodied in a circuit breaker operating means connected in an automatic reclosing system.

Although I have shown and described certain specific embodiments of my invention, I am fully aware that many modifications thereof are possible. My invention, therefore, is not to be restricted except insofar as is necessitated by the

prior art and by the spirit of the appended claims.

I claim as my invention:

1. In combination, a circuit breaker, operating means therefor including means for holding said breaker closed, means operable to cause opening of said breaker, closing means for closing said breaker, and means including a control switch for causing energization of said closing means to effect closing of said breaker, means operable only after said breaker has opened and immediately attempted to close a predetermined number of times in rapid succession for preventing further closing of said breaker, said means comprising an electrical charge storing means, means for charging said storing means a predetermined amount at each operation of said breaker by building up a potential difference in said charge storing means, and means actuated following an operation of said breaker at which the charge stored in said storing means has reached a predetermined potential for preventing further closing of said breaker.

2. In combination, a circuit breaker, operating means therefor including means for holding said breaker closed, means operable to cause opening of said breaker, closing means for closing said breaker, and means including a manually controlled switch for causing energization of said closing means to effect closing of said breaker, said breaker when opened remaining open until said manually controlled switch is closed; means operable only after said breaker has opened and immediately attempted to close a predetermined number of times in rapid succession for preventing further closing of said breaker, said means comprising a spring, means for stressing said spring a predetermined amount at each operation of said breaker to store energy therein, and means actuated when a predetermined amount of energy is stored in said spring for preventing further closing of said breaker.

3. In combination, a circuit breaker, operating means therefor including means for releasably holding the breaker closed, means operable to cause opening of the breaker, closing means for closing the breaker, and means including a switch for causing energization of said closing means to effect closing of said breaker, means operable only after said breaker has opened and immediately attempted to close a predetermined number of times in rapid succession for preventing further closing of said breaker, said means comprising a first charge storing means, means actuated during each opening operation of the breaker for charging said first charge storing means, a second charge storing means, means actuated upon each closing operation of the breaker for transferring the charge from said first charge storing means to said second charge storing means, and means actuated by the charge on said second charge storing means when its charge attains a predetermined value for preventing further closing of the breaker.

4. In combination, a circuit breaker, operating means therefor including means for releasably holding the breaker closed, means operable to cause opening of the breaker, closing means for closing the breaker, and means including a switch for causing energization of said closing means to effect closing of said breaker, means operable only after said breaker has opened and immediately attempted to close a predetermined number of times in rapid succession for preventing further closing of said breaker, said means comprising a first charge storing means, means ac-

tuated during each opening operation of the breaker for charging said first charge storing means, a second charge storing means, means actuated upon each closing operation of the breaker for transferring the charge from said first charge storing means to said second charge storing means, and means actuated by the charge on said second charge storing means when its charge attains a predetermined value for preventing further closing of the breaker, and means for discharging said second charge storing means at a predetermined slow rate.

5. In combination, a circuit breaker, operating means therefor including means for releasably holding the breaker closed, means operable to cause opening of the breaker, closing means for closing the breaker, and means including a switch for causing energization of said closing means to effect closing of said breaker, means operable only after said breaker has opened and immediately attempted to close a predetermined number of times in rapid succession for preventing further closing of said breaker, said means comprising a first charge storing means, means actuated upon each opening operation of the breaker for charging said first charge storing means, a second charge storing means, means actuated upon each closing operation of the breaker for transferring the charge from said first charge storing means to said second charge storing means, and means actuated by the difference of potential produced by the charge on said second charge storing means when its charge attains a predetermined value for preventing further closing of the breaker.

6. In combination, a circuit breaker, operating means therefor including means for releasably holding the breaker closed, means operable to cause opening of the breaker, closing means for closing the breaker, and means including a switch for causing energization of said closing means to effect closing of said breaker, means operable only after said breaker has opened and immediately attempted to close a predetermined number of times in rapid succession for preventing further closing of said breaker, said means comprising a first charge storing means, means actuated upon each opening operation of the breaker for charging said first charge storing means, a second charge storing means, means actuated upon each closing operation of the breaker for transferring the charge from said first charge storing means to said second charge storing means, and means including an electric discharge valve actuated when the difference of potential of the second charge storing means attains a predetermined value for preventing further closing of said circuit breaker.

7. In combination, a circuit breaker, operating means therefor including means for releasably holding the breaker closed, means operable to cause opening of the breaker, closing means for closing the breaker, and means including a manually controlled switch for causing energization of said closing means to effect closing of said breaker, means operable only after said breaker has opened and immediately attempted to close a predetermined number of times in rapid succession for preventing further closing of said breaker, said means comprising a first charge storing means, means actuated during each opening operation of the breaker for charging said first charge storing means, a second charge storing means, means actuated upon each closing operation of the breaker for transferring the charge from said first charge storing means to said second charge storing means, and means including an electric discharge valve actuated when the difference of potential of the second charge storing means attains a predetermined value for preventing further closing of said circuit breaker.

charge from said first charge storing means to said second charge storing means, and means including a glow tube connected to said second charge storing means rendered conductive when the difference of potential on said second charge storing means attains a predetermined value to cause said last mentioned means to prevent further closing of said breaker.

8. In combination, a circuit breaker, operating means therefor including means for releasably holding the breaker closed, means operable to cause opening of the breaker, closing means for closing the breaker, and means for causing energization of said closing means to effect closing of said breaker, means operable only after said breaker has opened and immediately attempted to close a predetermined number of times in rapid succession for preventing further closing of said breaker, said means comprising a first charge storing means, means actuated during each opening operation of the breaker for charging said first charge storing means, a second charge storing means, means actuated upon each closing operation of the breaker for transferring the charge from said first charge storing means to said second charge storing means, and means including a glow tube connected to said second charge storing means rendered conductive when the charge on said second charge storing means attains a predetermined value and an electric discharge valve having a control circuit to which the glow tube is connected, said discharge valve being actuated when said glow tube is rendered conductive to cause said last-mentioned means to prevent further closing of said breaker.

9. In combination, a circuit breaker, operating means therefor including closing means for closing said breaker, means for releasably holding said breaker closed, means operable to cause opening of said breaker, a circuit for causing energization of said closing means having in series therein an auxiliary switch which is closed when the breaker opens and a control switch, said operating means being subject under certain abnormal conditions to cause said breaker to open and immediately attempt to close an indefinite number of times in rapid succession as long as said control switch is held closed; and means operable only after said breaker has opened and immediately attempted to close a predetermined number of times in rapid succession for preventing said closing means from further closing said breaker, said means comprising a capacitor, means for charging said capacitor at each operation of said breaker, and means actuated by the charge on said capacitor when its charge attains a predetermined value for preventing further energization of said closing means.

10. In combination, a circuit breaker, operating means therefor including closing means for closing said breaker, means for releasably holding said breaker closed, means operable to cause opening of said breaker, a circuit for causing energization of said closing means having in series therein an auxiliary switch which is closed when the breaker opens and a control switch, said operating means being subject under certain abnormal conditions to cause said breaker to open and immediately attempt to close an indefinite number of times in rapid succession as long as 70 said control switch is held closed; and means operable only after said breaker has opened and immediately attempted to close a predetermined number of times in rapid succession for preventing said closing means from further closing said

breaker, said means comprising a capacitor, means for charging said capacitor at each operation of said breaker, and means including a relay actuated by the charge on said capacitor 5 when its charge attains a predetermined value for opening and holding open the circuit which causes energization of said closing means.

11. In combination, a circuit breaker, operating means therefor including closing means for closing said breaker, means for releasably holding said breaker closed, means operable to cause opening of said breaker, a circuit for causing energization of said closing means having in series therein an auxiliary switch which is closed when the breaker opens and a control switch, said operating means being subject under certain abnormal conditions to cause said breaker to open and immediately attempt to close an indefinite number of times in rapid succession as long as 20 said control switch is held closed; and means operable only after said breaker has opened and immediately attempted to close a predetermined number of times in rapid succession for preventing said closing means from further closing said breaker, said means comprising a capacitor, means for charging said capacitor at each operation of said breaker, and means actuated by the charge on said capacitor when its charge attains a predetermined value for preventing further energization of said closing means, and means for discharging said capacitor at a predetermined slow rate.

12. In combination, a circuit breaker biased to open circuit position; operating means therefor 35 including means for releasably holding said breaker closed, means operable to release said holding means to cause opening of the breaker, power operated closing means for operating the breaker to closed position upon energization of said closing means, circuit means including a manual closing control switch and an auxiliary switch on the breaker which is closed immediately the breaker opens, for effecting energization of the closing means to close the breaker when the 40 manual closing control switch is closed, said operating means being subject under certain abnormal conditions to cause said breaker to open and immediately attempt to close an indefinite number of times in rapid succession as long as 45 said manually operable closing control switch is held closed; and means operable only after said breaker has opened and immediately attempted to close a predetermined number of times in rapid succession for preventing further operation 50 of said closing means; said means comprising an energy storing device, means independent of the value of current in the main circuit of the breaker for transmitting a predetermined quantity of energy to said storing means upon each 55 operation of the breaker, a normally closed lock-out switch included in said circuit means, and means responsive to the condition of said energy storing device for opening said lockout switch to prevent further operation of said closing means 60 when a predetermined amount of energy has been stored in said energy storing device.

13. In combination, a circuit breaker biased to open circuit position, operating means therefor including means for releasably holding the breaker closed, means operable to release said holding means to cause opening of the breaker, power operated closing means for operating the breaker to closed position upon energization of said closing means, a closing relay having a winding operable when energized to cause a closing 75

operation of said closing means, circuit means including a manual closing control switch and an auxiliary switch on the breaker which closes immediately the breaker opens, for energizing the closing relay to effect closing of the breaker when the manual closing control switch is closed, said operating means being subject under certain abnormal conditions to cause said breaker to open and immediately attempt to close an indefinite number of times in rapid succession as long as said manually operable closing control switch is held closed; and means operable only after said breaker has opened and immediately attempted to close a predetermined number of times in rapid succession for preventing further closing of said breaker, said means comprising an energy storing device, means operated only when the breaker is operated for causing the transmission of a predetermined quantity of energy to said storing means upon each operation of said breaker, and a normally closed lockout switch included in said circuit means, and means responsive to the condition of said energy storing device for opening said lockout switch to prevent further closing of the breaker following an operation at which the energy stored in said energy storing device has reached a predetermined amount, and means for slowly dissipating the energy stored in said storing device.

14. In combination, a circuit breaker biased to open circuit position, operating means therefor including means for releasably holding the breaker closed, means operable to release said holding means to cause opening of the breaker, power operated closing means for operating the breaker to closed position upon energization of said closing means, circuit means including a manual closing control switch and an auxiliary switch on the breaker which is closed by the time the breaker reaches open position, for effecting energization of said closing means to cause closing of the breaker when said manual closing control switch is closed, said operating means being subject under certain abnormal conditions to cause said breaker to open and immediately attempt to close an indefinite number of times in rapid succession as long as said closing control switch is held closed; and means operable only after said breaker has opened and immediately attempted to close a predetermined number of times in rapid succession for preventing further closing of said breaker, said means comprising an energy storing device, means independent of the value of the current flowing in the main circuit of the breaker for transmitting a predetermined quantity of energy to said storing means upon each operation of said breaker, and means actuated by said energy storing device following an operation at which the energy stored therein has reached a predetermined amount for preventing further closing of said breaker by said manually operable closing control switch, and means for slowly dissipating the energy stored in said storing means.

15. In combination, a circuit breaker biased to open circuit position, operating means therefor including power operated closing means for operating the breaker to closed position upon energization of said closing means, means for releasably holding said breaker closed, means operable to release said holding means to cause opening of said breaker, a circuit for causing energization of said closing means having in series therein an auxiliary switch which is closed immediately the breaker opens and a manually operable closing

control switch, said operating means being subject under certain abnormal conditions to cause said breaker to open and immediately attempt to close an indefinite number of times in rapid succession as long as said manually controlled switch is held closed; and means operable only after said breaker has opened and immediately attempted to close a predetermined number of times in rapid succession for preventing further closing of said breaker, said means comprising an energy storing device, means independent of the value of current flowing in the main circuit of the breaker for transmitting a predetermined quantity of energy to said storing means upon each operation of said breaker, a normally closed lockout switch connected in series in the circuit with said auxiliary switch and said manually operable closing control switch, and means for opening said lockout switch when said energy storing means has attained a predetermined amount of energy for preventing further operation of said closing means.

16. In combination, a circuit breaker biased to open circuit position, operating means therefor including power operated closing means for operating the breaker to closed position upon energization of said closing means, means for releasably holding said breaker closed, means operable to release said holding means to cause opening of said breaker, a circuit for causing energization of said closing means having in series therein an auxiliary switch which is closed immediately the breaker opens and a manually operable closing control switch, said breaker when opened remaining open until said manually controlled switch is closed, said operating means being subject under certain abnormal conditions to cause said breaker to open and immediately attempt to close an indefinite number of times in rapid succession as long as said manually controlled switch is held closed; and means operable only after said breaker has opened and immediately attempted to close a predetermined number of times in rapid succession for preventing further closing of said breaker, said means comprising an energy storing device, means independent of the value of current flowing in the main circuit of the breaker for transmitting a predetermined quantity of energy to said storing means upon each operation of said breaker, a lockout relay having normally closed contacts connected in series in the circuit with said auxiliary switch and said manually operable control switch, and means for actuating said lockout relay when said energy storing device has attained a predetermined amount of energy, to open and hold open the circuit which causes energization of said closing means.

17. In combination, a circuit breaker, operating means therefor including power operated closing means for operating the breaker to closed position upon energization of said closing means, means for releasably holding said breaker closed, means operable to cause opening of said breaker, a circuit for causing energization of said closing means having in series therein an auxiliary switch which is closed immediately the breaker opens and a manually operable closing control switch, said operating means being subject under certain abnormal conditions to cause said breaker to open and immediately attempt to close an indefinite number of times in rapid succession as long as said manually controlled switch is held closed; and means operable only after said breaker has opened and immediately attempted to close a predetermined number of times in rapid

succession for preventing further closing of said breaker, said means comprising an energy storing device, means movable upon each operation of the breaker for causing the transmission of a predetermined quantity of energy to said storing means each time the breaker is operated to one of its positions, and a normally closed lockout switch connected in series in the circuit with said auxiliary switch and said manually operable closing control switch, said lockout switch being actuated by said energy storing device when said storing device has attained a predetermined amount of energy, for opening and holding open the circuit which causes energization of said closing means.

18. In combination, a circuit breaker biased to open circuit position, operating means therefor including means for releasably holding the breaker closed, means operable to release said holding means to cause opening of the breaker, closing means for closing the breaker, circuit means including a manual closing control switch and an auxiliary switch on the breaker which is closed when the breaker is open, for causing energization of said closing means to close the breaker, said operating means being subject under certain abnormal conditions to open and immediately attempt to close an indefinite number of times in rapid succession as long as said manual control switch is closed, and means operable only after said breaker has opened and immediately attempted to close a predetermined number of times in rapid succession for preventing further closing of said breaker, said means comprising a fluid storing container, means for storing a predetermined quantity of fluid energy in said container upon each operation of the breaker, means actuated following an operation at which a predetermined quantity of fluid energy has been stored in said container, for preventing further closing of said breaker, and means for slowly dissipating the fluid energy stored in said container.

19. In combination, a circuit breaker biased to open circuit position, operating means therefor including means for releasably holding the breaker closed, means operable to release said holding means to cause opening of the breaker, closing means for closing the breaker, circuit means including a manual closing control switch, and an auxiliary switch on the breaker which is closed when the breaker is open, for causing energization of said closing means to close the breaker, said operating means being subject under certain abnormal conditions to open and immediately attempt to close an indefinite number of times in rapid succession as long as said manual control switch is closed, and means operable only after said breaker has opened and immediately attempted to close a predetermined number of times in rapid succession for preventing further closing of said breaker, said means comprising an electrical charge-storing device, means for storing a predetermined quantity of electric energy in said charge-storing means upon each operation of the breaker, means actuated

5 following an operation at which the energy stored in said storage device has reached a predetermined amount, for preventing further closing of the breaker by said circuit means, and a discharge means through which the charge in said storage device is slowly discharged.

20. In combination, a circuit breaker biased to open circuit position, operating means therefor including means for releasably holding the breaker closed, means operable to release said holding means to cause opening of the breaker, closing means for closing the breaker, circuit means including a manual closing control switch and an auxiliary switch on the breaker which is closed when the breaker is open, for causing energization of said closing means to close the breaker, said operating means being subject under certain abnormal conditions to open and immediately attempt to close an indefinite number of times in rapid succession as long as said manual control switch is closed, and means operable only after said breaker has opened and immediately attempted to close a predetermined number of times in rapid succession for preventing further closing of said breaker, said means comprising a spring, means for storing a predetermined quantity of energy in said spring by stressing said spring upon each operation of the breaker, means operable following an operation at which the energy stored in said spring has reached a predetermined amount, for preventing further closing of the breaker, and means for slowly dissipating the energy stored in said spring, said energy dissipating means comprising a retarding device for retarding the restoring action of said spring.

21. In combination, a circuit breaker biased to open circuit position, operating means therefor including means for releasably holding the breaker closed, means operable to release said holding means to cause opening of the breaker, closing means for closing the breaker, circuit means including a manual closing control switch and an auxiliary switch on the breaker which is closed when the breaker is open, for causing energization of said closing means to close the breaker, said operating means being subject under certain abnormal conditions to open and immediately attempt to close an indefinite number of times in rapid succession as long as said manual control switch is closed, and means operable only after said breaker has opened and immediately attempted to close a predetermined number of times in rapid succession for preventing further closing of said breaker, said means comprising a fluid container, means for supplying a predetermined quantity of fluid to said container upon each operation of the breaker, means operable following an operation at which the fluid supplied to said container has reached a predetermined amount, for preventing further closing of the breaker, said container having a slow leakage outlet for slowly dissipating the fluid stored in said container.
